UNITED STATES PATENT OFFICE.

MAURICE J. WOHL, OF LONG ISLAND CITY, AND MAX MAYER, OF NEW YORK, N. Y.,
ASSIGNORS TO M. J. WOHL & CO., INC., OF LONG ISLAND CITY, NEW YORK, A COR-
PORATION OF NEW YORK.

CONNECTION PLUG.

Application filed March 1, 1923. Serial No. 622,040.

This invention relates to improvements in electric connection plugs or couplings, especially adapted to connect separable sections of conductors in an electric circuit.

5 It is the object of the invention to produce a connection plug of the pin type in which the conducting cables or cords leading to and from the plug are anchored so that the terminal connections within the plug can 10 not be severed or injured by a strong pull on the cable, before the electrical connection made by the plug is opened.

It is a further object of the invention to relieve the insulating material of the plug 15 of strains produced by a pull on the cable and to improve the clamping means. With these and other objects in view, the invention consists in a reduction of the number 20 of parts composing the plug to a very small number and in a simplification of their design and arrangement which is hereinafter fully described and finally pointed out in the claims.

In the drawings which form a part of 25 these specifications:—

Fig. 1 is a sectional front elevation of a plug embodying the invention on lines 1—1 of Figs. 2—4—5. The covering is omitted on the upper half of the plug.

30 Fig. 2 is a side elevation of a plug embodying the invention.

Fig. 3 is a sectional side elevation of a plug on the line 3—3 of Fig. 1, showing the male and female parts separated and the 35 covering in opened position on the latter.

Fig. 4 is a sectional view of a plug on a plane indicated by the line 4—4 of Fig. 1, the terminals are removed from this figure.

Fig. 5 is a sectional view of a plug on 40 planes indicated by line 5—5 of Fig. 1, the terminals are shown in place in this figure.

Fig. 6 is a front elevation of one of the 45 four shells forming the covering of the plug.

Fig. 7 is a top-plan of Fig. 6.

This connection plug consists of two co-operating members 10 and 11 which are alike in construction with the only exception that the male part 10 is provided with binding posts 12 having plug ends 50 which fit into the socket apertures of binding posts 13 of the female part 11. The binding posts or terminals of either member are enclosed in the body part of the plug con-

sisting of two blocks of insulating material 14 and 15 preferably of the same size 55 and shape and closely abutting against each other on line 4—4 of Fig. 1. Block 14 is provided with two cylindrical apertures for the body part of the binding posts which rest against a shoulder 16 formed therein 60 near the dividing line of the two plug halves. Block 15 is provided with cylindrical apertures 17 arranged concentric with terminals 12 or 13 and of a diameter large and deep enough to accommodate the connection ends 65 of the terminals with their binding screws 18 and loops of the clamped conductors 21. The conductors are each led out of the insulating block 15 through two smaller apertures 19 and 20 of which the former extends concentric with 17 almost to the outer 70 face of 15 and apertures 20 which are spaced closer towards each other for accommodation of the converging conductors. Apertures 20 are slotted open at 29 towards one 75 side of the block 15 for easier insertion of the conductors. By spreading them apart the conductors become fastened in their final position in apertures 19 and 20. The binding posts 12 and 13 fit loosely in their enclosing apertures to facilitate the interchange of the female part of one plug with the male part of a different one without extreme accuracy in manufacturing.

The two insulating blocks 14 and 15 are 80 held together and covered by two metallic shells 30 which are shown in Figs. 6 and 7.

These shells are exactly alike in all particulars, so that four shells of the same kind 85 cover the male and female members of one complete plug. The blocks 14 of either member protrude a short distance beyond the shells towards each other to eliminate the possibility of electrical contact between the 90 shells of the two parts. Each shell consists of a thin metal sheet 30 which covers one half of the insulating blocks 14 and 15. The two shells which cover the same plug member 95 adjoin each other on the line 1—1 of Fig. 2; both are swingingly held on block 14 by means of pivot screws 22. These screws are lodged on the right hand side of the shell shown in Figs. 6 and 7 in a protruding ledge 31 provided with a plain aperture and on the left hand side of the shell in a tapped aperture of lug 32. It will be seen from 100 105

Fig. 5 that the two shells which form a covering couple, fit into each other at the sides of the plug when their inner faces are placed against each other, the tapped lug on 5 32 fitting into a semi-cylindrical recess at the inner side of the lug on ledge 31. Screws 22 enter a short distance into the block 14 serving the double purpose of forming a pivot for the swinging of the two shells into 10 the position shown in Fig. 3 and also to hold the blocks 14 and 15 together and within the covering. The neck of the plug is formed by the hollow cylindrical parts 33 provided on their inside with the corrugations 34 which grip the covering of the conductor cable 23 when flanges 35 are pressed against each other by means of the clamping screws 36. The flange 35 on the right hand side of each shell is provided with an open 15 hole 38 while that on the left hand side has a tapped boss 39, to provide a long thread for screw 36. The neck part 33 and body part 30 of the shells are joined by a funnel shaped portion 37 to permit spreading of the 20 conductors 21.

From the foregoing description it can be seen that the two shells which form the cover of each plug member coact with each other and with the insulating blocks enclosed by them to form a metallic and rigid jaw clamp for the conductor cable 23.

These clamping means depend nowhere on tension placed on screw threads cut into insulating material. The cable 23 is completely encircled by this clamp and a large exterior surface thereof is held under pressure which is practically uniform around its circumference. All current carrying bare parts are securely enclosed in heavy insulation and the conductors require no sharp bends for their connection. The covering also serves to hold the two blocks 14 and 15 in alinement with each other, as only one of the blocks (14) is fastened to the shells the other one 45 15 is held in its place by the shells and block 14, but the blocks are not tightly fitted to the shells to permit for expansion. The electric conductors are easily connected to the terminal binding posts of the plug and their assembling is greatly facilitated by the two slots 29 which make it possible to lay the conductors with their insulation and the connection loop formed thereon into their final 50 position and avoids bending of the loops after threading the conductors through apertures 20. A further advantage is to be found in the fact that the binding posts with their connecting screws 18 are completely rotatable on their axis within the 55 aperture 17, which eliminates the twisting of each conductor-loop into the position fixed by the direction of the flat part on the post when the latter can not assume any desired angle on the axis. The freedom of the terminals within their enclosure diminishes the 60

strain on the contact pins resulting from rough usage to which such plugs are exposed. Swelling or warping of the insulating material has practically no influence on the plug as this material is loosely held in 70 relation to the terminals as well as to the enclosing shells.

Having thus described our invention what we claim as new and desire to secure by Letters Patent is:

1. In a connection plug, an insulating block, a connection terminal held therein, a pair of shells alike in shape covering said body, jaws forming a clamping tube at the cable end of said shells an alining edge on one longitudinal side of each shell overlapping the outside of the other shell and pivot pins in said ledges near the terminal end of said plug forming means to oscillate said shells with their jaws, and means on said shells to press them and their jaws against each other.

2. A connection plug comprising an insulating body, an electrical contact held within an aperture of said body, a pair of metallic shells covering said body and overlapping each other transversely to their abutting faces at opposite sides of said body, said overlapping portions forming means to aline said shells with each other, pivots near one end of said overlapping shells and co-operating clamping jaws at the other end of said shells.

3. In a connection plug, a contact forming member comprising an insulating body, connection terminals held therein and a pair of jaw forming shells covering said body pivotally connected thereto, said pivot forming common means to hold said shells on said body and to permit their oscillation.

4. In a connection plug a pair of insulating blocks connection terminals enclosed therein, a pair of shells covering said blocks abutting against each other along a common plane, jaws forming a cable clamping means at one end of said shells, pivot pins near the other end thereof passing through both shells into the insulating material of one of said blocks, forming a fastening means to hold both blocks in said shells and to permit their oscillation for clamping a cable in said jaws.

5. In a connection plug, an insulating body a connection terminal enclosed therein a pair of shells enclosing said body abutting against each other at a common plane longitudinally of said plug, a recess and a ledge covering the same, formed at one side of each shell, said ledge extending transversely across said plane forming means for lateral alinement of said shells fitting into the recess of its companion shell making said shells overlapping and exchangeable with each other.

6. In a connection plug, a contact forming

member consisting of a pair of insulating blocks enclosing connection terminals and a pair of metallic shells covering both blocks, jaws on said shells to clamp a conductor 5 entering said plug and a ledge on only one side of each shell forming aligning means for the ledgeless side of the other shell and holding means to join said shells extending through said ledge into the body part of the 10 other shell.

7. In a connection plug, a male or female member, an insulating body and a pair of like covering shells exchangeable with each other abutting longitudinally of said body, 15 a lug on one side of each shell adapted to hold a pivot pin, a recess formed in the opposite side of each shell so that in covering position on said block the lug of each shell fits into the recess on the other shell and 20 forms a hinged joint by means of said pivot pin.

8. In a connection plug an insulating body holding terminal connectors a pair of shells enclosing said body divided along a common 25 plane a lug on one side of each shell, a pin held in said lug, a recess formed in the opposite side of each shell so that the lug of one shell occupies the recess of the other shell, said pin forming means to join said shell to each other and to hold said body 30 therein.

9. In a connection plug, terminal connectors, an insulating body enclosing them, a pair of shells covering said body abutting 35 against each other on a common plane, an aligning ledge on only one side of each shell, a pivot pin in each ledge near the terminal end of said plug passing through the side wall of the other shell and extending into 40 said insulating body, a pair of jaws formed by said shells at the opposite end of said plug, said pivot pin forming means to fasten said shells to said body and to permit their oscillation for clamping said jaws together.

45 10. In a connection plug a pair of insulating blocks a pair of terminal connectors enclosed thereby, the stem of each connector being enclosed in one of said blocks and the wire holding end in the other block, a pair of covering shells enclosing both blocks, a pair of jaws adapted to hold a cable formed by said shells, pivot pins forming means to oscillate said shells passing therethrough 50

into said stem-holding block and means on said jaws to press them against each other. 55

11. A connection plug comprising an insulating body, a contact forming member enclosed therein, a casing for said body consisting of two shells abutting against each other along a common plane passing longitudinally through the axis of said contact forming member, pivot pins joining said shells having their common axis in said dividing plane placed at the contact forming end of said plug, a single jaw on each shell 60 and means to join said shells arranged perpendicularly to said pivot pins at the opposite end of said plug, said shells being mounted to rotate on the axis of said pivot pins to form two single armed levers for 70 pressing said jaws against each other.

12. A connection plug comprising an insulating body a terminal therein, a casing for said body consisting of two shells abutting against each other on a common plane a ledge 75 on one side of each shell overlapping the other side of the adjoining shell, a pivot pin in each ledge extending into the side of the other shell to hinge the two parts of the casing together at one end thereof, to form two 80 single armed levers by means of said shells, a clamping jaw formed at the other end of each shell rotatable about said pivot pin and means at the free end of the levers formed by said shells to press them against each 85 other.

13. In a connection plug a terminal connector at one end thereof a pair of insulating blocks each partly enclosing said connector and a casing for said blocks consisting of two like counterparts each having a lug on one of its sides and a recess formed on its opposite side, fitting into a similar recess and lug of the other shell to make the shells exchangeable with each other and 95 means formed by parts of said casing to clamp a conductor leading to said terminal.

14. In a connection plug a pair of insulating blocks holding a connection terminal, a pair of covering shells for said blocks, one 100 of said blocks being pivotally fastened to both shells and the other block being loosely enclosed by said shells.
